UNITED STATES PATENT OFFICE.

WILLIAM C. WINFIELD, OF WARREN, OHIO, ASSIGNEE TO THE WINFIELD MANUFACTURING COMPANY, OF WARREN, OHIO, A CORPORATION.

TUBULAR LANTERN.

No. 914,688.

Specification of Letters Patent.

Patented March 9, 1909.

Application filed August 20, 1908. Serial No. 449,516.

To all whom it may concern:

Be it known that I, WILLIAM C. WINFIELD, a citizen of the United States, residing at Warren, in the county of Trumbull and State of Ohio, have invented certain new and useful Improvements in Tubular Lanterns, and do declare that the following is a full, clear, and exact description of the invention, which will enable others skilled in the art to 10 which it appertains to make and use the same.

My invention relates to improvements in tubular lanterns, and the invention consists in means for holding the globe guard and globe at any desired elevation so that the 15 lantern may be lighted, all substantially as shown and described and particularly pointed out in the claims.

In the accompanying drawings, Figure 1 is a side elevation of a lantern embodying 20 my invention with one of the side tubes partially in section and showing the globe guard down on its seat. Fig. 2 is a vertical sectional elevation of a portion of one of the side tubes and one of the friction engaging 25 devices for the globe guard and a portion of a side wire of said guard engaged by said device and held as occurs when the globe is raised from its seat, as hereinafter fully described. Fig. 3 is a detail of one of the 30 said friction engaging devices, and Fig. 4 is a plan view on line $x-x$, Fig. 1.

The invention is comprised in the parts thus shown and described and particularly in the means for frictionally engaging the 35 side wires W of the globe guard or frame and thus supporting the said guard with the globe at any preferred elevation above its seat, assuming that such elevation or lift is sufficient to enable one to light the lantern 40 with a match or taper. The said side wires W have a slight lateral or outward bend or depression 3 of approximately V shape in their lower portions adapted to engage the horizontal wire H of the globe guard on 45 their inside, and said side wires are straight and parallel or substantially parallel with each other from said bends 3 downward to the right angled bend 10, as seen in Figs. 1 and 2, and which straight portion is indicated 50 by numeral 2. At their upper ends the said side wires W connect with the edge of the canopy C by pivot as usual, and said canopy is slidably mounted upon the central draft tube D.

55 A feature in side wires W to be noted is

that said wires run at an inclination between the canopy and bends 3, while the lower portions 2 of said wires are offset inward somewhat at said bends and stand vertical from that point down to angle or corner 10, thus 60 bringing the two portions of said wires into different vertical planes in side view and causing a distinct pull or draw to be made upon the said friction members F when the globe guard is raised and the said members 65 or devices are forced out of the recesses or bends 3 and into engagement with the straight wire portions 2 below the same. The outward bends or depressions 3 in the side wires therefore serve not only as a point 70 of engagement with and for the horizontal guard wire H, but also as a place of retirement for the hook or loop 5 of the friction spring supporting members F. To this end the said members or devices are preferably 75 made of spring wire fashioned to be bodily inserted into the side tubes T of the lantern and have straight body portions 6, spring stems 7 and U shaped bends 8 connecting body and stem, while the other end 9 is bent 80 at right angles in the plane of stem 7 and projects inward through a hole in the tube T and is formed with a hook 5 outside said tube and engaged over wire W. In point of location said loop or hook comes almost 85 directly opposite depression 3 in the side wire W when the globe is down upon its seat, as in use, and therefore is normally engaged or lies in said depression or bend just below wire H as a place of rest, and at which time 90 its spring action is at its minimum. This appears by reference to Fig. 1, in which the globe is seated and the bodies 6 of said spring devices F are pressed back against the wall of the tubes and their hooks 5 are drawn 95 back into said depressions 3 by the spring action of stem 7 bearing against the opposite sides of said tube. On the other hand when the globe is raised, as presumably in Fig. 2, the main portion 6 of the device is sprung 100 outward somewhat in its lower portion against the resistance of its own spring end 7 and the hook or loop 5 is carried down out of its retirement in bend 3 onto the straight portion 2 of the wire, where the friction is 105 sufficient to hold the globe in raised position. Hence the globe is held higher or lower by the said spring devices at any desired elevation by a sliding contact on a perfectly plain and straight surface. It will be no- 110

ticed that the engagement of loops or hooks 5 of the said friction sustaining members F is with the wires W on the inner side and that suspension or support of the globe begins as soon as said hooks or loops 5 leave the depressions 3 and enter upon said straight portions 2. It is to be noticed, also, as a peculiarity of this construction, that the said spring members F are wholly retired within 10 in the side tube of the lantern and hence entirely out of the way mechanically and out of sight except in their small and almost unnoticeable projecting portions 5. This both contributes to the attractiveness of the lantern in point of appearances and keeps the main operating members within cover so as to avoid possible injury by accident and exposure to the elements.

In the operation the tube D at the top and 20 the friction members F at the sides in conjunction with the side wires W serve as guides for directing the said guard in direct up and down movements under such frictional tension by the said members F that 25 the guard is held up at any point of engagement on the straight portions 2 of the guard wires, and there is no special stopping point necessary for the guard.

What I claim is:—

- 30 1. A lantern having side tubes and a globe-guard with vertical side wires, and springs within the said tubes having ends projecting through the inner sides thereof and frictionally engaging said side wires.
- 35 2. A lantern having side tubes and a guard with side wires, and a spring device confined within each tube having engagement with the corresponding side wire of the guard and adapted to spring back and forth in the wall 40 of the tube.

3. A lantern having side tubes with holes through the inner sides thereof and a globe guard having side wires next thereto, in combination with springs located within said tubes having substantially loop shaped portions extending outward through said holes and having sliding engagement with the said side wires. 45

4. A lantern having side tubes and a spring device confined in each tube having a portion 50 extending through the tube, in combination with a globe guard having vertical side wires provided with bends in their lower portions in sliding relation with said yielding portions of said spring devices. 55

5. A lantern having side tubes, a device located in each tube having a spring portion at one end confined in the tube and a projection at the other end extending through the wall of the tube, in combination with a globe 60 guard having side wires provided with outward depressions and straight portions beneath said depressions operatively engaged by said side projections.

6. A lantern having side tubes and a central tube at its top, in combination with a globe guard and canopy slidably engaged with said central tube, and guides located in said side tubes having spring stems at one end and right angled hook shaped projections at the other end extending through holes in said side tubes and engaging the inner surface of the side wires of the globe 70 guard.

In testimony whereof I sign this specification in the presence of two witnesses.

WILLIAM C. WINFIELD.
